(57) **CLAIM**

The ornamental design for a camera remote control holder, as shown and described.

DESCRIPTION

FIG. 1 is a front, top, right perspective view of a first embodiment of a camera remote control holder showing our new design;

FIG. 2 is a rear, left perspective view thereof;

FIG. 3 is a top plan view thereof; and

FIG. 4 is a cross sectional view thereof cut along the line 4-4 of FIG. 3.

FIG. 5 is a front, top, left perspective view of a second embodiment of a camera remote control holder showing our new design;

FIG. 6 is a front, bottom, right perspective view thereof;

FIG. 7 is a front elevational view thereof;

FIG. 8 is a partially enlarged front, top, left perspective view along the lines 8-8 of FIG. 5;

FIG. 9 is a partially enlarged front, bottom, right perspective view thereof along the lines 9-9 of FIG. 6;

FIG. 10 is a partially enlarged front elevational view along the lines 10-10 of FIG. 7;

FIG. 11 is a cross sectional view cut along the line 11-11 of FIG. 10.

FIG. 12 is a front, top, right perspective view of a third embodiment of a camera remote control holder showing our new design;

FIG. 13 is a front, bottom, right perspective view thereof;

FIG. 14 is a front elevational view thereof;

FIG. 15 is a partially enlarged front, top, right perspective view thereof along the lines 15-15 of FIG. 12;

FIG. 16 is a partially enlarged front, bottom, left perspective view thereof along the lines 16-16 of FIG. 13;

FIG. 17 is a partially enlarged front elevational view thereof along the lines 17-17 of FIG. 14; and,

FIG. 18 is a cross sectional view cut along the line 18-18 of FIG. 17.

The broken lines in the drawings depict environmental subject matter and portions of the camera remote control holder that form no part of the claimed design. Dot-dash

(Continued)

broken lines define the boundaries of the claimed design, but form no part of the claimed design.
